(57) **CLAIM**

The ornamental design for a sanding tool attachment for a power tool, as shown and described.

DESCRIPTION

FIG. 1 is a right side, front perspective view of a sanding tool attachment for a power tool shown mounted to a reciprocating power tool;

FIG. 2 is another right side, front perspective view thereof; FIG. 3 is a left side, rear perspective view thereof;

FIG. 4 is a rear perspective view thereof;

FIG. 5 is a front elevation view thereof;

FIG. 6 is a left side elevation view thereof;

FIG. 7 is a top plan view thereof; and,

FIG. 8 is a bottom plan view thereof.

A right side elevation view of the sanding tool attachment for a power tool of FIG. 1 is a mirror image of the left side elevation view of FIG. 6.

In the drawings, portions of the sanding tool attachment for a power tool located between the break lines represent indeterminate length and form no part of the claimed design. The broken lines in the drawings are for the purpose of illustrating portions of the article and environmental structure that form no part of the claimed design.
